UNITED STATES PATENT OFFICE.

NATHAN T. COFFIN, OF KNIGHTSTOWN, INDIANA.

HANGING SAWS.

Specification of Letters Patent No. 9,856, dated July 19, 1853.

To all whom it may concern:

Be it known that I, NATHAN T. COFFIN, of Knightstown, in the county of Henry and State of Indiana, have invented a new and useful Improvement in Hanging Mill Saws; and I do hereby declare that the following is a full, clear, and exact description of the construction and operation of the same, reference being had to the annexed drawings, forming part of this specification, in which—

Figure 1 is a front elevation of the saw gate, and fender beams and posts, showing the guides, and manner of hanging the saw. Fig. 2 is a section upon the line $x\ y$ of Fig. 1. Fig. 3 is a top view of the saw gate showing the contrivances for adjusting the saw. Fig. 4 is a horizontal section upon the line $y\ y'$ of Fig. 1 on an enlarged scale. Fig. 5 is section upon line $z\ z'$ Fig. 1, large scale. Fig. 6 is vertical section on line $x^2\ x^2$ Fig. 1.

Similar letters in the several figures refer to the same parts of the machine. In the drawings (A, A') represent the fender posts, (B, B') the fender beams, (C) the saw gate, (D) the saw, (E) the upper stirrup and (E') the lower. These stirrups are constructed in the usual manner, except that the upper one (E) fits the gate stile loosely, so as to conform to the movements of the regulating screws; the saw is drawn up and tightened in the usual manner by the nuts (a, a') upon the bolts (b, b') of the stirrup (E), but the cap (c) is furnished with the knife edge projection (c'), upon its under side, which projection works in the concavity or groove (d) in the plate (d') upon the top of the upper stile of the gate (C).

The adjusting apparatus consists of the straps (e, e'), plates (f, f'), (g, g'), and (h, h') and screws (k, k'), (l, l'), and (m, m'). The straps (e, e') are secured to the upper stile of the gate (C), the plates (f, f') pass through it, on each side of the stirrup bolts (b, b'), being kept in position by the screws (k, k'); the plates (g, g') are notched to rest upon the plates (f, f') and are held in front and rear of the stirrup (E) by the screws (l, l'). The plates (h, h') embrace the lower stirrup (E') by means of bolts passing through their extremities; and have the screws (m, m') working through them to the face of the saw.

The guide consists of the frame (F) suspended to the fender beam (B) by the journals and bearings (F', F''); and the slide (G) having a vertical motion under the straps (n, n'), at the lower extremity of which slide is the horizontal arm (H), formed of two jaws embracing the saw D; these jaws are furnished with the wooden followers (o, o'), regulated by the temper screws (p, p'); and through the jaws are the channels q, q' for the passage of oil to the saw; the slide (G) is held at any required point by the screws (s) passing through the straps (n, n').

The operation of my machine is as follows: The saw being placed in the stirrups in the usual manner it is drawn moderately tight by the nuts (a, a'), its position regulated laterally by the screws (k, k' and m, m'), and the requisite pitch given by the screws (l, l') after which the tightening is completed. The saw hung as above stated, the guide frame (F) is let down, and the slide (G) lowered to the proper distance, and fastened by the screws (s), the followers (o, o') are adjusted by the temper screws (p, p') so that the saw will glide easily between them, and the machine is ready for use.

The advantages resulting from my method of hanging and guiding are well worthy of attention. The pitch of the saw can be regulated with great facility to the different sizes of logs, by the screws (l, l'). This is very essential, as small logs require the saw to be more nearly vertical than those of large dimensions; and by my method of hanging this is accomplished easily and effectively. The knife edge (c') and hollow, or grooved plate (d') permit the stirrup to be moved backward or forward without binding or twisting the stile of the saw gate, as would be the case if the cap rested directly upon its top.

This method of hanging the saw admits of its being removed, and again returned to its original position, by simply removing the tightening nuts (a, a') and loosening the screws (m) or (m') on one side of the lower stirrup (E'). By this operation we are enabled to take the saw from the stirrups leaving the adjusting plates and screws in such positions that the saw when returned will be hung precisely as it was before removal.

The guiding apparatus being suspended as I propose, furnishes the means of removing it when not required for use, and thus forms a decided improvement over the usual method of sliding guide which always obstructs the gate.

What I claim as my invention and desire to secure by Letters Patent, is—

The combination of the stirrup hung upon a knife edge, with the adjusting screws t, t' ,

for the purpose of regulating the rake of the saw in the manner described.

In testimony whereof I have hereunto signed my name before two subscribing witnesses.

N. T. COFFIN.
